UNITED STATES PATENT OFFICE.

FREDERICK W. COOK, OF SAN FRANCISCO, CALIFORNIA.

SAW-MILL SET-WORKS.

SPECIFICATION forming part of Letters Patent No. 410,349, dated September 3, 1889.

Application filed April 24, 1889. Serial No. 308,488. (No model.)

To all whom it may concern:

Be it known that I, FREDERICK W. COOK, of the city and county of San Francisco, State of California, have invented an Improvement 5 in Saw-Mill Set-Works; and I hereby declare the following to be a full, clear, and exact description of the same.

My invention relates to the class of saw-mill set-works, and especially to the lever 10 mechanism by which the set-works are operated; and my invention consists in the hereinafter-described novel mechanism for obtaining accurate fractional movements of the works.

15 The object of my invention is to provide a simple and effective means for readily and accurately limiting and defining the movement of the set-lever.

Referring to the accompanying drawings 20 for a more complete explanation of my invention, Figure 1 is a side elevation of my improvement. Fig. 2 is a plan of the same.

A is one of the sills or beams of the saw-mill carriage.

25 B is the set-shaft, which extends on one side longitudinally of said carriage and communicates movement to the screws at each end, which operate the knees of the set-works, it being unnecessary herein to show said screws 30 and knees.

Upon the set-shaft and suitably connected therewith and arranged in relation thereto is the mechanism represented by D, and which affects the movement of the set-shaft, the particular description and operation of said mechanism being unnecessary, as it forms no part 35 of my invention.

E is the vibrating set-lever which operates the mechanism D. Its lower end or foot is 40 double or forked and extends up on each side of the set-bar F. This bar is pivoted at one end at the point f and has on its other end a handle portion f', provided with a spring-controlled pawl f'', the end of which is adapted 45 to engage the curved rack G, which is fixed in position and is provided with a series of holes g. The set-bar F has near its pivoted end the series of shoulders or stops f', which are properly graduated, as shown.

50 Between the forked foot of the set-lever is a stop-block e, which is adapted to come in

contact with any of the shoulders or stops f' of the set-bar F. Now, by freeing the pawl end of the bar F and moving it up or down on the rack G the shoulders or stops of said bar F are thrown severally into the path of the stop-block e of the set-lever. For example, if a one-inch board is to be made, the bar F is raised on its pivotal center until its pawl f'' engages the uppermost hole g of the rack G, 55 and in this position the first shoulder or stop of bar F is thrown into the path of the stop-block e of the lever E, thereby limiting the movement of the lever. If a sixteenth is to be added, the pawl end of the set-bar F is 60 dropped down to the second hole of the rack G, so that the second shoulder or stop of the bar is thrown into the path of the stop-block e of the lever E, its first shoulder or stop being dropped low enough to allow said stop-block 65 to pass it. Therefore the lever can move a farther distance, so as to set the knees up a sixteenth more, and so on throughout the series, the bar F moving down on its pivotal center, lowering all the preceding shoulders or stops 70 and bringing the proper one into the path of the stop-block, this movement being determined by the engagement of the handle end of the bar with the fixed rack G, the holes of which are properly separated and graduated 75 80 to correspond with the shoulders or stops of said bar.

Pivoted upon a bolt passing through the lever E is an approximately U-shaped stop-piece H, having its hub formed with notches 85 which are engaged by a spring h, the said piece carrying also at its free end a screw and adjusting-nut, as shown. The piece H is thrown into use by dropping its end down, so that it will come in contact with the shoulders or stops of the set-bar F, thus limiting 90 the movement of the lever E.

I is the fixed limiting-stop for defining the back limit of the lever.

Having thus described my invention, what 95 I claim as new, and desire to secure by Letters Patent, is—

1. In saw-mill set-works, and in combination with the vibrating set-lever, the pivoted swinging set-bar having a series of shoulders 100 or stops, a fixed rack for limiting and defining the movement of the set-bar, and a

stop on the set-lever for coming in contact with any of the shoulders or stops of the set-bar, according to the position of said bar, substantially as described.

5. 2. In saw-mill set-works, and in combination with the vibrating set-lever, the pivoted swinging set-bar having the series of shoulders or stops, the fixed rack having a series of holes corresponding with the shoulders or stops of the set-bar, a pawl on the end of the set-bar adapted to engage the holes of the fixed rack, and a stop on the set-lever for coming in contact with any of the shoulders or stops of the set-bar, according to the position of said bar, substantially as described.

15. 3. In saw-mill set-works, and in combination with the set-lever having a forked or divided lower portion, the pivoted swinging set-bar passing through said lower portion of the set-lever and having a series of shoulders or stops, the fixed rack for limiting and defining the movement of the set-bar, and a stop-block between the members of the lower por-

tion of the lever for coming in contact with any of the shoulders or stops of the set-bar, 25 according to its position, substantially as described.

4. In saw-mill set-works, and in combination with the vibrating set-lever having a stop-block, the pivoted swinging set-bar having a series of shoulders or stops with which the stop-block of the lever is adapted to come in contact, the fixed rack for engaging the end of the set-bar and limiting and defining its movement, and the pivoted swinging stop-piece on the lever adapted to be thrown down to come in contact with the shoulders or stops of the set-bar to provide for the saw-kerf, 30 substantially as described.

35. In witness whereof I have hereunto set my hand.

FREDERICK W. COOK.
